CLAIM

The ornamental design for a dual food container, as shown and described.

DESCRIPTION

FIG. 1 is a perspective view of the dual food container of the present invention;

FIG. 2 is an exploded view thereof;

FIG. 3 is a left view of FIG. 1;

FIG. 4 is a right view of FIG. 1;

FIG. 5 is a front view of FIG. 1;

FIG. 6 is a rear view of FIG. 1;

FIG. 7 is a top view of FIG. 1;

FIG. 8 is a bottom view of FIG. 1;

FIG. 9 is a perspective view of FIG. 1 with the top lid removed for clarity of illustration; and,

FIG. 10 is a top view of FIG. 9.

The broken lines shown represent unclaimed subject matter and form no part of the claimed design.
